UNITED STATES PATENT OFFICE.

JOHN E. WOODBURY, OF WORCESTER, MASSACHUSETTS.

APPARATUS FOR PRINTING.

1,209,097.

Specification of Letters Patent.

Patented Dec. 19, 1916.

Application filed June 4, 1913. Serial No. 771,668.

To all whom it may concern:

Be it known that I, JOHN E. WOODBURY, a citizen of the United States, residing at Worcester, in the county of Worcester and 5 State of Massachusetts, have invented a new and useful Apparatus for Printing, of which the following is a specification.

This invention relates to an apparatus for printing designs and illustrations from intaglio plates.

Considerable difficulty has been encountered in doing commercial printing from intaglio plates involving illustrations, because the tinted or half tone parts of the 15 design will not print clearly under ordinary conditions. This is of particular importance in cases involving both illustrations and reading matter which is the usual condition presented in this class of printing.

20 Although the invention relates broadly to this art as specified above, regardless of the particular applications thereof, it is especially applicable to the printing of high class letter-heads and advertisements of various kinds in which it is desired to secure the highest degree of perfection in the printing of illustrative designs of more or less complicated nature. It is well understood that for the purpose of printing such 25 designs, the paper should be moistened, but this has always presented difficulties for the reason that it is difficult to handle moistened sheets at a high enough rate of speed and with sufficient accuracy to do this class of 30 printing within a reasonable cost and yet keep the quality of the highest degree. I have discovered that it is possible to secure the highest class of results by the local moistening of the sheet within the space occupied by the illustration.

This invention, therefore, relates to the apparatus by which this method can be carried out, and to details of construction and combinations of parts involved in such apparatus.

Reference is to be had to the accompanying drawings, in which—

Figure 1 is a side view of a well known kind of plate press showing a preferred embodiment of this invention applied thereto; Fig. 2 is a front elevation of the same; Fig. 3 is a transverse sectional view on the line 3—3 of Fig. 2 on enlarged scale; Fig. 4 is a side view showing a modification and simplification of the apparatus, and Fig. 5 is a

plan of a letter-head printed in accordance with this invention.

The invention is shown as applied to a printing press of well known type having a frame 10. This frame is provided with the usual power shaft 12 and rotary members 13, the connections between which will not be described herein or shown in full as they are well understood in this art. Connected with these rotary members is an arm or lever 14 connected with a link 15 and operating a slide 16 in a well known way to move it forward and back in guides on the frame. The intaglio plate 17 is held in position below an opening in the feed table 18 which has a slight vertical motion. The paper to be printed upon is registered by the registering devices 19 on the feed table in the usual way. Then a plunger 20 ascends, moving the plate up through the feed table against the counter 21. These parts also are well understood, and any desired mechanism can be employed for this purpose, this invention being independent of any particular style of press.

Mounted over an outwardly extending portion 24 of the base of the frame is a platform 25 preferably on about the same level as the feed table when moved up. On this platform are registering devices 26 corresponding with the registering devices 19 for receiving the sheets before they are put into the press proper. The side registers on the platform are shown on the left and those for the press on the right.

Connected with the arm 14 is a flexible connection 30. This is shown as passed around pulleys 31 and connected by a metal connection 32 with the end of a belt 33. This belt is made of a strip of textile material which is capable of taking up moisture and having that moisture spread throughout a given portion thereof, so as to be uniformly dampened. At the other end this flexible belt is connected by a clamp 34 or the like through another connection 32 with a flexible member 35 which passes over pulleys 36 and is connected with an arm 37 secured on the same shaft as the arm 14 and oscillatable therewith. A slide 38 is connected with the belt and slides along a stationary frame 39 to guide the belt and keep it from flapping. In this way the movement of the arm 14 in one direction is accompanied by the movement of the arm 37, and

the two together work the two ends of the combined flexible member, so that the oscillation of these arms causes this belt 33 to move back and forth.

5 The path of the belt is shown more fully in Fig. 3. It passes under a roller 40 and over a roller 41 which is adjustable by a screw 42. These rollers are mounted on an extension of the platform 25. It then passes 10 adjacent to the registers 26 and under the position which the sheet occupies when registered therein. It then passes over a roller 43 down to the lower clamp 34. On the platform 25 is a block 44 which is provided 15 with a projection 45. This projection extends up into contact with this flexible belt and is of the same size and shape as the illustrative portion of the design of the intaglio plate used on the press and of the counter. It is also located in the same position with respect to the registers 26 that this design on the plate is to the registers 19.

An arm 47 is eccentrically connected with one of the rotary members 13 and pivoted 25 to a lever 48 to which is connected a pivoted platen 49 directly over the block 44. This also is shown as provided with a projection 50 and as being covered with a textile water absorbing sheet 51. This projection registers with the projection 45. These parts 30 obviously work with the press and for each revolution of the press the platen moves down once substantially in contact with the block 44.

35 Over the belt 33 on the platform 25 is located a stationary sheet 52 which is made of textile material capable of absorbing and holding moisture. This is stretched out between a plate 53 and a clamping member 54 and is shown as of two thicknesses. It is directly upon this that the paper sheet A is located.

In a convenient position is arranged a water pipe 56 having a nozzle 57 with an adjustable valve 58 arranged over the path of the movable belt 33 and not far from the rolls 40 and 41. This valve can be adjusted to any desired flow of water. The belt shifter 60 which controls the starting and 50 stopping of the press in the usual way is provided with an extending end 61 which engages and operates the stem 62 of a controlling valve 63 which permits the operator when shifting the belt to turn on or off 55 the water in the pipe.

When the water is turned on it will drip constantly on the belt in accordance with the adjustment of the valve 58. The water dropping on the belt obviously would 60 spread to some extent by itself but would not spread uniformly under all conditions, and would leave the belt with the most moisture at the center. For the purpose of thoroughly spreading the moisture, the belt 65 is passed over the rolls 40 and 41. This

squeezes the moisture from the center to the edges and keeps the moisture uniform across the belt.

Another important feature in connection with the moistening of the paper consists in 70 the provision of means whereby the pressure on the paper first insures the application of a spot of moisture to the double sheet 52 and applies that moisture with pressure to the sheet of paper. The projections 45 and 75 50 hold the paper and belt away from the block 44 and platen 49 and thus prevent the application of moisture beyond their areas. Then as the platen ascends the removal of the pressure permits the absorbent material 80 of the sheet 52 and belt 33 to take up any excess of moisture from the paper, thus preventing the paper being made too wet. Thus the spot is moistened uniformly, and 85 all the sheets are moistened to the same degree. It will be understood readily that the excessive wetting of a small spot on a sheet of paper would tend to swell the paper very badly at the moistened spot, and thus make it difficult to handle and difficult to impress 90 it with the design properly without wrinkling or smutting. The primary object of the sheet 52 is to provide a stationary support for the paper.

The paper having been moistened and the 95 moisture having been absorbed, to leave the moisture in a proper condition thereon, the sheet is transferred from the registers 26 to the registers 19. This can be done obviously automatically or by hand, but in the 100 present case the invention is shown as applied to a hand press, and it is intended that the operator shall take the sheets one at a time from the moisture registers and apply them to the printing registers. This is done 105 at the time when the platen 49 is moving up and when the pressure members of the press are separated. At the same time the printed sheet is being removed. The motion of both 110 hands of the operator in taking the sheet from the moisture applying mechanism and putting it into the press and taking the other sheet from the press and piling it up at the side is in the same direction and at the same time. Consequently it does not materially add to the skill or rapidity required 115 of the operator.

In Fig. 5 the sheet A is shown with an 120 illustrative design B and the dotted line C indicates the extent of the application of moisture. It will be seen that the printed matter is not included in the part which is moistened unless it is necessary to provide the printing in the design itself. In this way it will be seen that a uniform, but not 125 excessive, moisture is applied to each sheet localized over that portion thereof which is to receive the imprint involving the illustrative, that is the tinted or half tone, portion or portions, and the printing is done 130

immediately after the moisture is applied and the excess removed. The perfectly black parts of the design, if they can be separated from the remainder, and the reading matter, do not need this treatment.

5 In the form of the invention shown in Fig. 4, the arrangement of the belt 33 is substantially the same, except that one end is directly connected and the other almost directly connected with two arms 65 and 66 which are mounted on the same shaft 67. This is a shaft added to the printing machine, and is operated by a link motion 68 from the arm 14. The same principles apply, however.

15 Although I have illustrated and described only two ways of carrying out the invention I am aware of the fact that many modifications can be made therein without departing 20 from the scope of the invention as expressed in the claims. Therefore I do not wish to be limited in these respects but

What I do claim is:—

25 1. In an intaglio printing device, the combination with means for moistening a portion of a sheet to be printed, and means for keeping the remainder of the sheet dry, of means for making the impression from the 30 illustrative portion of an intaglio plate on the moistened portion of the sheet.

35 2. In an apparatus for printing from intaglio plates, the combination with means for locally moistening a portion of the sheet, means for preventing the spreading of the moisture beyond the moistened portion, means for removing any excess of moisture, and means for printing the illustrative portion of the design from the intaglio plate on the moistened portion of the sheet, and the 40 reading matter on the dry portion.

45 3. In an intaglio printing machine, the combination with an intaglio printing plate, of means for moistening a sheet to be printed locally on that portion which is to receive an imprint from the intaglio plate.

50 4. The combination with an intaglio plate having an illustrative design, of means for locally moistening a sheet on which the imprint is to be made, and means for printing thereon from the plate while the sheet is in that condition.

55 5. The combination with an intaglio plate having an illustrative design, and means adjacent thereto for registering a sheet in position to receive an imprint therefrom, of a second means for registering the sheet, and means for applying moisture to those portions of the sheet which register with the illustrative portions of the plate while the 60 sheet is held by said second registering means.

65 6. The combination with means for holding an intaglio plate having an illustrative design, means adjacent thereto for registering a sheet in position to receive an imprint

from such plate, of a second means for registering the sheet, and means adjacent to the second registering means for applying moisture to certain portions of the sheet, and for taking up the excess moisture to secure a 70 uniform moistening effect.

7. In a printing machine, the combination with means for holding an intaglio plate, means for making an impression with said plate upon a sheet, the last named means comprising a movable member, and means connected with and operated by said movable member for applying moisture to the portion of the sheet which registers with the illustrative portions of the intaglio plate. 80

8. In a printing machine, the combination with an intaglio plate having illustrative portions thereon, a movable member on the machine, means connected with said movable member for making an impression with said plate, means for registering a sheet in position to receive said impression, a second means for registering the sheet, and means connected with said movable member for applying moisture to the portion of the sheet in position to receive the imprint of the illustrative portions of the plate when said sheet is located by said second registering means. 90

9. In a printing machine, the combination with a register for the sheets, a second register for the sheets adjacent to the first, an intaglio plate having an illustrative portion located in position for printing adjacent to the first registering device, a block 100 having a projecting portion corresponding with the position and shape of the illustrative portion of the intaglio plate located in the same relative position to the second registering device as the intaglio plate is to the first, and means for locally moistening a sheet in position over said block. 105

10. In a printing machine, the combination with a register for the sheets, a movable feed table, means for moving said feed table, a second register for the sheets adjacent to the first, an intaglio plate having an illustrative portion located in position for printing adjacent to the first registering device, a block having a projecting portion corresponding with the position and shape of the illustrative portion of the intaglio plate located in the same relative position to the second registering device as the intaglio plate is to the first, and means connected 110 with said feed table operating means for locally moistening a sheet in position over said block. 115

11. In a printing machine, the combination with a register for the sheets, a second register for the sheets adjacent to the first, an intaglio plate having an illustrative portion located in position for printing adjacent to the first registering device, a block having a projecting portion corresponding with the 125

position and shape of the illustrative portion of the intaglio plate located in the same relative position to the second registering device as the intaglio plate is to the first, 5 a moistening device, means for moving the moistening device over said block, a platen movable adjacent to said second registering device, and means for operating the platen to press upon a sheet in the second register- 10 ing device.

12. In a press, the combination with a registering device, of a block located therein and having a projecting portion, a moisture holding piece of sheet material located parallel with said block, a platen movable toward and from said block, and means for operating the platen, whereby the moisture holding sheet will be pressed by the platen against a sheet of paper held by the register- 15 tering device.

13. In a press, the combination with a registering device, of a block located therein and having a projecting portion, a moisture holding piece of sheet material located over 20 said block, a platen movable up and down toward said block, means for operating the platen, whereby the moisture holding sheet will be pressed by the platen against a sheet of paper held by the registering device, a 25 stationary sheet located above the first named sheet, and means for moving the first named sheet periodically.

14. In a printing machine, the combination with means for operating a platen comprising an oscillatable arm, of a second arm 30 connected with said oscillatable arm to move therewith, flexible connections connected with each of said arms, a strip of sheet material connected at its ends with said flexible 35 material, a registering device for a sheet, a connection, means for guiding said sheet of material along said registering device, and means for pressing a paper against said sheet of material.

40 15. In a printing press, the combination with an oscillatable arm, of means connected with said arm for making an impression, a

flexible connection connected with said arm and movable therewith, a piece of sheet material connected with the flexible connection 50 at one end, means at the other end of said flexible material for moving it back and forth, a registering device for the paper, means for guiding the sheet material along said registering device under the paper 55 therein, means for moistening said sheet material, and means connected with said oscillatable arm for applying pressure to the paper when over said sheet material.

16. In a printing press, the combination 60 with a registering device for sheets of paper, rollers arranged adjacent thereto, a strip of sheet material passing over said rollers and along the registering device under the paper therein, means connected with the 65 ends of said strip of material for shifting it back and forth, means for constantly applying moisture to said strip of material, and means for pressing the paper over said material in the registering device. 70

17. In a printing press, the combination with a registering device for sheets of paper, of rollers arranged adjacent thereto, a strip of sheet material passing over said rollers and along the registering device, means connected with the ends of said strip of material for shifting it back and forth, means 75 for constantly applying moisture to said strip of material, a stationary strip of moisture absorbing material located adjacent to the first named strip of material in the registering device, and means for pressing paper against said material. 80

18. The combination with means for printing from an intaglio plate, of means for locally moistening the sheet where it receives the illustrative portion of the design. 85

In testimony whereof I have hereunto set my hand, in the presence of two subscribing witnesses.

JOHN E. WOODBURY.
